(57) **CLAIM**

The ornamental design for a bench, as shown.

DESCRIPTION

FIG. 1 depicts a top perspective view of the bench of the invention.

FIG. 2 depicts a bottom perspective view of the bench of the invention.

FIG. 3 depicts a front orthogonal view of the bench of the invention.

FIG. 4 depicts an orthogonal left side view of the bench of the invention.

FIG. 5 depicts an orthogonal right side view of the bench of the invention.

FIG. 6 depicts an orthogonal top view of the bench of the invention; and,

FIG. 7 depicts an orthogonal bottom view of the bench of the invention.
